CHAIR BASE

William H. McKinley, Youngstown, Ohio, assignor to The General Fireproofing Company, Youngstown, Ohio, a corporation of Ohio

Application April 2, 1958, Serial No. 50,292

Term of patent 14 years

(Cl. D15—8)

Fig. 1 is a top plan view of the chair base embodying my new design.

Fig. 2 is a side elevation of the chair base shown in Figure 1.

Fig. 3 is a bottom plan view of the chair base shown in Figs. 1 and 2.

Fig. 4 is a sectional view taken on the line 4—4 of Fig. 1.

Fig. 5 is a sectional view taken on the line 5—5 of Fig. 2.

Fig. 6 is a perspective view of the chair base shown in Figs. 1-3.

I claim:

The ornamental design for a chair base, as shown.
